UNITED STATES PATENT OFFICE.

DAVID WEBER, OF PHILADELPHIA, PENNSYLVANIA, ASSIGNOR TO DAVID WEBER AND COMPANY, OF PHILADELPHIA, PENNSYLVANIA, A COPARTNERSHIP.

BOX-STAY.

1,196,319.

Specification of Letters Patent. Patented Aug. 29, 1916.

Application filed December 16, 1911. Serial No. 666,228.

To all whom it may concern:

Be it known that I, DAVID WEBER, a citizen of the United States, and a resident of Philadelphia, in the county of Philadelphia, 5 and State of Pennsylvania, have invented certain new and useful Improvements in Box-Stays, of which the following is a specification.

This invention relates to shipping cases, 10 boxes, cartons, etc., especially such as are made of paste-board, corrugated paper-board, or of any other material possessing a considerable degree of rigidity, but also liable to be crushed, cut or broken.

15 One of the objects of this invention is to provide a stay to embrace the walls of a box so as to hold them together and adapted to reinforce the walls.

Another object of this invention is to provide a cushion for a box.

20 A further object is to provide a stay to embrace the walls of a box and adapted to reinforce the edges between the walls.

A still further object of this invention is 25 to provide a stay adapted to prevent a tie-rope from cutting the box.

With these objects in view, my invention consists of the method and means for accomplishing the aforesaid and other objects 30 as will be hereinafter more fully described and claimed and illustrated in the accompanying drawing, it being understood that changes in minor details may be made within the scope of my claim without departing 35 from the spirit or sacrificing any of the advantages of this invention.

Figure 1, of the drawing is a perspective view of a folder or blank, and of a cord or cable; Fig. 2 is a perspective view of the 40 cross-section of a stay formed from the folder and cable, and along the dotted lines shown in Fig. 1; Fig. 3 is a perspective view of a carton provided with my stays; Fig. 4 is an upright view thereof shown 45 partly in cross-section; Fig. 5 is a perspective view of a packer provided with my stays, and Fig. 6 is a perspective view of a section of a box provided with my stay for protecting it from the tie-rope.

50 Similar figures refer to similar parts throughout the several views.

1 indicates a folder or blank, and 2 a cord or cable. The stay illustrated in Fig. 2 is made by folding a strip of flexible material,

like paper or pasteboard, in the shape of 55 the blank 1 over the cord 2 along the dotted lines shown in Fig. 1. The cord 2 constitutes the core embedded in the tubular ridge 3, beyond which the folds of the strip are joined to form a flange 4. 60

The stay, formed as described above, is mounted around the walls of a box, with its ridge 3 along the line formed by the junction of the hold with a cover. Thus, in 65 Figs. 3 and 4, the stay is shown to embrace the walls 6, holding them together at the joints 7. The flanges 4, of the stay, reinforce the walls, as at 5, and the ridges 3 protect the edges between the covers and walls, as at 8, whether the box is in the position 70 shown in Fig. 3 or that shown in Fig. 4.

Fig. 5 illustrates a cover 9 and a hold 10 thereunder. The cover is provided with a frame adapted to be telescoped on the hold, the joints 12 of the cover being adapted to 75 register with those of the hold. The walls 13 of the cover are joined by the flange 4 of my stay which supports the ridge 3 on the edge 14. As shown, the hold 10 is similarly joined, the flange 4 supporting the ridge 3 80 on the bottom edge.

Fig. 6 illustrates the application of my stay for protecting a box to prevent a tie-rope from cutting or crushing it. The ridge 3, above the flange 4 of my stay mounted 85 on one of the walls 17, protects the edge 16, where the walls are joined, from the rope 15, the cord 2 embedded in the stay preventing the rope from cutting through.

Having thus described my invention, what 90 I claim as new and desire to protect by Letters Patent, is—

The combination with a receptacle, of a reinforcing attachment, comprising a flexible member folded upon itself, said flexible 95 member having a tubular formation at the juncture of the resultant leaves, said tubular formation being diagonally offset from the receptacle and its closure, and having inserted therein a reinforcing core. 100

In testimony whereof I have signed this specification in the presence of two subscribing witnesses.

DAVID WEBER.
